SHOE HEEL

Edward S. Bosch, Saltsburg, Pa., assignor, by
mesne assignments, of one-third to George R.
Compton, Saltsburg, Pa.

Application July 28, 1943, Serial No. 496,471

1 Claim. (Cl. 36—36)

The present invention relates to new and useful improvements in shoe heels, and has for its primary object to provide, in a manner as herein-after set forth, a novel construction and arrangement whereby the heels of a pair of shoes may be expeditiously removed and interchanged.

Another very important object of the invention is to provide a calk-equipped heel member which, when desired, may be expeditiously mounted on a shoe.

Other objects of the invention are to provide a shoe heel of the character described which will be comparatively simple in construction, strong, durable, attractive in appearance, and which may be manufactured at low cost.

All of the foregoing, and still further objects and advantages of the invention will become apparent from a study of the following specification, taken in connection with the accompanying drawings wherein like characters of reference designate corresponding parts throughout the several views, and wherein:

Figure 1 is a bottom perspective view, showing a shoe heel constructed in accordance with the present invention.

Figure 2 is a bottom plan view of the metallic stationary and removable plates, showing said plates separated.

Figure 3 is a fragmentary view in vertical section, showing the method of attaching the rubber heel to the removable plate.

Figure 4 is a bottom perspective view of another form of the invention.

Figure 5 is a cross-sectional view through the modification.

Figure 6 is a detail view in perspective of the calk-receiving plate of the modification.

Figure 7 is a fragmentary view in vertical longitudinal section, showing the means for releasably securing the removable plate in position on the stationary plate.

Referring now to the drawings in detail, it will be seen that reference numeral 1 designates a metallic plate which is adapted to be permanently mounted in position beneath the rear portion of a shoe 2. Toward this end, the stationary plate 1 has formed therein a plurality of openings 3 which accommodate rivets or other suitable fasteners for firmly securing said plate in position beneath the shoe. Formed beneath the plate 1 is a dove tail tongue 4 of a shape corresponding substantially to that of said plate. The tongue 4 extends from the breast or front of the plate 1 to a point in spaced relation to the rear end thereof.

Removably mounted on the plate 1 is a metallic plate 5. Extending into the plate 5 from its forward end to a point in spaced relation to its rear end is a dovetail groove or channel 6 which receives the correspondingly shaped tongue 4. A screw 7 is threadedly mounted at 8 on the forward end portion of the plate 5 and is engageable with the plate 1 for securing said plate 5 in position thereon. The plate 5 has formed therein a plurality of openings 9.

Mounted on the plate 5 is a rubber lift 10. Tubular rivets 11 are placed in the rubber lift 10 and project from the upper face thereof. As illustrated to advantage in Figure 3 of the drawings, the tubular rivets 11 are engaged and expanded in the openings 9 for permanently and firmly securing the members 5 and 10 together.

It will thus be seen that a construction and arrangement has been provided whereby the rubber member 10, which constitutes the wearing portion of the heel, may be expeditiously removed when desired. This may be accomplished by simply turning the screw 7 and slipping the plate 5 rearwardly off the plate 1, as illustrated in Figure 2 of the drawings. As will be readily apparent, the wearing portions of the heels of a pair of shoes may be readily interchanged.

It will be noted that the head of the screw 7 is engageable with the forward end of the plate 1 for retaining the plate 5 thereon. It will also be observed that this screw head includes a flat side. Thus, it is only necessary to give the screw one-half of a turn to secure or release the plate 5.

In the embodiment of Figures 4, 5 and 6 of the drawings, a leather lift 12 is firmly secured in any suitable manner on the slidably removable metallic plate 5 in lieu of the rubber lift 10. The leather lift 12 has recessed into its lower face and flush therewith a metallic plate 13 having openings 14 therein. The openings 14 accommodate ice calks 15 which project from the plate 13. As best seen in Figure 5 of the drawings, the calks 15 include threaded, tapered end portions 16 which are screwed into the leather lift 12. The calks 15 further include flanges 17 at an intermediate point which are engageable with the plate 13. The flanges 17 are notched (see Fig. 4) to receive a suitable tool for inserting and removing the calks 15.

It will thus be seen that an ice creeper has been provided which may be expeditiously mounted for use on a pair of shoes. As the calks 15 wear and become blunt or broken, they may be readily removed for replacement.

It is believed that the many advantages of a

shoe heel constructed in accordance with the present invention will be readily understood, and although preferred embodiments of the device are as illustrated and described, it is to be understood that further modifications and changes in the details of construction may be resorted to which will fall within the scope of the invention as claimed.

What is claimed is:

In a detachable shoe heel, a rigid metal plate conforming in size and shape to the heel portion of a shoe bottom and having apertures to facilitate its attachment to the latter, said plate having an integral longitudinal dovetailed tongue on its upper side of a shape corresponding to that of the plate, said tongue being spaced from the sides and rear end and extending to the breast

5 of the plate, a second rigid metal plate having a longitudinal dovetail groove cut in its upper surface and snugly receiving the correspondingly shaped tongue, said groove being spaced from the sides and rear end of and opening hatch in the breast of the second-named plate, said second-named plate having apertures to facilitate attachment of a lift thereto and being provided at its breast with a central lug, and a screw threaded into said lug with its head engaging the breast of the first-named plate to retain the second-named plate thereon, said screw having its head cut away at one side to disengage from the first-named plate when the screw is given a partial 15 turn.

EDWARD S. BOSCH.
